UNITED STATES PATENT OFFICE.

SAMUEL F. DOUGLASS, OF PRAIRIE DU ROCHER, ILLINOIS, ASSIGNOR TO VEHICLE SIGNAL COMPANY, A CORPORATION OF ARIZONA.

VEHICLE-SIGNAL.

1,238,750.

Specification of Letters Patent.

Patented Sept. 4, 1917.

Application filed March 5, 1914. Serial No. 822,726.

To all whom it may concern:

Be it known that I, SAMUEL F. DOUGLASS, a citizen of the United States, residing at Prairie du Rocher, in the county of Randolph and State of Illinois, have invented certain new and useful Improvements in Vehicle-Signals; and I do hereby declare the following to be a full, clear, and exact description of the invention, such as will enable others skilled in the art to which it appertains to make and use the same.

My invention relates to new and useful improvements in vehicle signals and resides in the provision of a direction indicating device for vehicles, particularly automobiles, and which will operate to indicate to vehicles that the driver contemplates making a turn going forward or stopping.

An important object of my invention is to provide a simple and inexpensive signaling device which is readily operable from the driver's seat and cheap to install and manufacture.

Another important object of my invention is to provide a device of the character described which is simple as to construction, reliable and efficient in operation, capable of being readily attached to vehicles and is cheap to manufacture.

The above and additional objects are accomplished by such means as are illustrated in the accompanying drawings, described in the following specification and then more particularly pointed out as claimed.

Figure 1 is a diagrammatic view of the electrical circuit employed to operate the signals.

Fig. 2 is a vertical sectional view taken through the signal showing the detail construction thereof,

Fig. 3 is a front elevation of the signaling device showing a portion of the glass cover broken away,

Fig. 4 is a detail sectional view of the reflector for the electrical lamp, and

Fig. 5 is a detail perspective view of one of the reflectors.

The signaling device comprises a preferably circular and metallic casing 4, which comprises a bottom or base wall 5 and a circular flange or wall 6 that is formed integral with the periphery of the wall 5. Mounted within the casing 4 upon the wall 5 and arranged radially about the center of the cas-

ing is a plurality of channel shaped reflectors 7 that are preferably V-shaped in cross section and arranged with their outer ends engaging the wall 6 of the casing and their inner ends in spaced relation to the center of the casing. Suitable electric lamps 8 are mounted within the reflectors and are received by cylindrical shaped bodies 8' that are formed of suitable insulating material and extended through the rear wall 5 of the casing 4 and through the reflectors 7 and serve to hold the latter in position, and the wires connecting the lamps with a source of current extend through an opening 9 in the center of the casing as shown. Mounted upon a circular flange 10 that is arranged within the casing and extends at right angles from the wall 6 thereof adjacent but spaced from the outer edge of the wall 6 is a circular plate or disk 11 that is provided with a plurality of radially extending arrow slots 12 therein. These arrow slots 12 are arranged to align and be disposed parallel with the reflectors 7 so that the light from the lamps 8 is thrown through the arrow slots 12.

Mounted within the casing with its periphery in engagement with the inner face of the wall 6 of the casing is a glass plate 13 that is provided with a circular central portion that is colored green and designated 14 while the rest of the plate is stained or otherwise suitably colored red. An angular, circular and threaded ring 15 is turned upon the wall 6 of the casing and has an angular portion disposed in engagement with the glass plate 13 adjacent the periphery thereof to secure the plate 13 in position. The glass plate 13 is translucent and arranged so that the arrow indications will only be visible from the illumination of the lamps. The center portion of the arrow indications will be shown green and the shaft and head portion red. The horizontal arrow slot 12 will indicate the right and left turning.

As a means for individually lighting the lamps 8, I provide a switch designated 16 as an entirety that is to be arranged upon the steering column of the automobile or some other place adjacent to the driver's seat. This switch 16 comprises a body plate 17 having pivoted on the central portion thereof a switch arm 18 that is arranged to coöperate with a plurality of spaced con-

tact points 19 arranged adjacent the periphery of the plate 17 which is preferably circular.

With particular reference to Fig. 1 where-
 5 in I have illustrated a diagrammatic view
 of the electrical circuit I employ, the nu-
 meral 20 designates a battery or other suit-
 able source of current. A conducting wire
 10 connects one side of the battery or other
 suitable source of current 20 with the piv-
 oted switch arm 18. A conducting wire 22 is
 connected with the other side of the battery
 and to the signaling device. Eight con-
 ducting wires 24 connect the wire 22 with
 15 the eight lamps 8 in the signaling device.
 Two sets of conducting wires 25 and 26 con-
 nect the lamps 8 with the contact points 19
 on the switch 16. If desired, a pair of sig-
 naling devices can be employed and mount-
 ed, respectively, at the forward and rear of
 20 the vehicle and the wires 25 and 26 con-
 nected up with both signaling devices and
 the sets of wires 25 and 26 are shown ex-
 tended beyond their connections for the
 25 switch 16 in Fig. 1 for this purpose. When
 a pair of signaling devices is thus employed
 a conducting wire 27, similar to the wire 22
 for the signal shown in Fig. 1, is extended
 from the battery to the other signaling de-
 30 vice, not shown, and is adapted to be con-
 nected to the lamp of the last-mentioned
 signaling device in the same manner as the
 wire 22 is connected with the lamps 8 of
 the device shown in Fig. 1. The contact
 35 points 19 and coöperating conducting wires
 are so arranged that when the switch arm 18
 is moved to the right the signal to indicate
 that the driver is contemplating making a
 right turn is operated since the lamps are
 40 illuminated and the signal displayed. Upon
 the turning of the switch arm 18 to engage
 the opposite contact point the left hand sig-

nal for indicating that the driver is going
 to take to left turn is displayed and so on.

It will be readily seen that I have pro-
 45 vided a simple and inexpensive direction in-
 dicating device which will simultaneously
 operate signals at the front and rear of a
 vehicle.

In practice, I have found that the form 50
 of my invention, illustrated in the drawings
 and referred to in the above description, as
 the preferred embodiment, is the most effi-
 cient and practical; yet realizing that the
 55 conditions concurrent with the adoption of
 my device will necessarily vary, I desire to
 emphasize the fact that various minor
 changes in details of construction, propor-
 tion, and arrangement of parts may be re-
 60 sorted to when required, without sacrific-
 ing any of the advantages of my invention,
 as set forth.

What is claimed is:—

In a vehicle signal, a casing, a plate with-
 in said casing and having a plurality of 65
 radial slots therein, means for holding the
 plate in position, a plurality of elongated
 reflectors arranged within the casing and in
 rear of the plate and alining with the slots
 70 in the plate and each of the reflectors con-
 sisting of a rear wall and outwardly diverg-
 ing side walls, elements extending through
 one of the walls of the casing and through
 the rear walls of the reflectors for holding
 75 the reflectors in operative position within
 the casing, and lamps supported by the ele-
 ments.

In testimony whereof I affix my signature
 in presence of two witnesses.

SAMUEL F. DOUGLASS.
